F. E. DODGE,
CRACKING SOLVENT NAPHTHA,
APPLICATION FILED JULY 17, 1918.

1,409,893.

Patented Mar. 14, 1922.

UNITED STATES PATENT OFFICE.

FRANK E. DODGE, OF FLUSHING, NEW YORK, ASSIGNOR TO THE BARRETT COMPANY,
A CORPORATION OF NEW JERSEY.

CRACKING SOLVENT NAPHTHA.

1,409,893.

Specification of Letters Patent. Patented Mar. 14, 1922.

Application filed July 17, 1918. Serial No. 245,380.

To all whom it may concern:

Be it known that I, FRANK E. DODGE, a citizen of the United States, residing at Flushing, in the county of Queens and 5 State of New York, have invented certain new and useful Improvements in Cracking Solvent Naphtha, of which the following is a specification.

This invention relates to a process of heating hydrocarbons of high boiling points in 10 order to obtain valuable hydrocarbons of lower boiling points. It relates more specifically to the heating of solvent naphtha in order that its constituents may be "cracked" 15 to produce benzol, or toluol, or both.

The invention may be conveniently carried out by passing the solvent naphtha, or other hydrocarbon which it is desired to crack, over the surface of highly heated coke 20 which remains in the ovens at or near the end of the coking operation in the usual gas-making or coke-producing operations.

The invention will be readily understood from the accompanying somewhat diagrammatic drawing in which,

Fig. 1 is a longitudinal section through an oven, and,

Fig. 2 is a section taken along the line A—A of Fig. 1.

30 In these drawings, reference character 1 represents a horizontal oven that may be charged with a charge of coal 2 through inlets 3. Outlet for the coke which has been produced by the coking operation is shown 35 at 4. Means for heating the oven 1 are shown at 5, 6 and 7. 5 is the fuel gas mains, 6 are the flues in which the gas is burned, and 7 are the regenerators which alternately are heated by the products of 40 combustion and heat the air used to burn the gas, in the well known manner.

A receptacle 10, for solvent naphtha or other hydrocarbon to be cracked, has leading from it pipe 11 closed by valve 12. The 45 pipe 11 extends into the upper portion of oven 1. The pipe 13 for gases leads to main 14 from the upper portion of oven 1.

The operation is as follows: Coal 2 is charged into the oven 1 through inlets 3. 50 The oven 1 is heated as is usual in the ordinary processes of gas manufacture and coke making. The volatile constituents pass off through pipe 13 into main 14 from which the gases are passed through the usual scrubbers, etc., to render them suitable for use.

At or near the end of the coking operation, in which all or a large portion of the volatile matters have been driven off, and while the coke 2 is at an elevated temperature, say around 600° to 800° C., the valve 60 12 is opened in order to permit the naphthas to enter the oven 1 through pipe 11 into the space above the heated coke 2.

It is thus seen that the practice of this process does not necessitate the installation 65 of a large amount of expensive apparatus, but may be carried out by a slight addition to apparatus already in use. It does not require a substantial increase in the amount of heat used in coking or gas-making 70 operations, as the hot mass of coke remaining at the end of the ordinary coking process contains enough heat to crack a substantial amount of solvent naphthas. Just before the coking operation has been entirely completed the valve 12 may be closed, and after the coking operation is completed the mass 75 is removed through outlet 4 and a new charge of coal is introduced through inlets 3 and the same process, as above described, 80 is repeated with the fresh batch.

Solvent naphthas consist largely of xylenes and some mesitylenes which, upon being subjected to the high temperature in oven 1, lose one or more CH_2 groups, being thereby converted into toluol or benzol. The 85 solvent naphthas which are heated by this process may be obtained from any convenient source, such as the destructive distillation of coal. Any portion of the 90 naphthas which may have passed through unchanged and been collected, may be separated from the benzol and toluol and again passed through the heated space in order to be cracked.

It is to be understood that instead of passing the naphthas over the coke in the oven where it has been produced, the coke may first be removed to a different closed chamber where the naphthas may be passed over 100 its surface while it is still hot, in order to crack the naphthas.

Claims:

1. The process of cracking solvent naphthas which consists in passing said naphthas over the surface of coke near the end of the coking operation while the temperature is about 600° C. to 800° C.

2. The herein described process which comprises the steps of introducing aromatic 110

hydrocarbons of high boiling points into the hot space above coke in a coke oven while the temperature is about 600° C. to 800° C. and collecting the products.

5 3. The process of cracking solvent naphthas which consists in introducing said naphthas into the upper portion of a coke oven after the coal therein has been substantially coked, and while the temperature 10 is about 600° to 800° C.

4. The herein described process of producing benzol and toluol which comprises the steps of introducing solvent naphthas into the heated space above the hot coke in 15 a coke oven while the temperature is about 600° C. to 800° C. and collecting the products thereby formed.

5. The herein described process of producing benzol and toluol which comprises 20 the steps of introducing xylol into the

heated space above the hot coke in a coke oven while the temperature is about 600° C. to 800° C. and collecting the products thereby formed.

6. The herein described process of producing benzol and toluol which comprises the steps of introducing solvent naphthas into the heated space above the hot coke in a coke oven and collecting the products thereby formed while the temperature is 25 about 600° to 800° C.

7. The herein described process of producing benzol and toluol which comprises the steps of introducing xylol and mesitylene into the heated space above the hot coke in a coke oven and collecting the products thereby formed while the temperature is about 600° C. to 800° C.

In testimony whereof I affix my signature.
FRANK E. DODGE.
